CLAIM

The ornamental design for a laser biostimulator for veterinary and human use, as shown and described.

DESCRIPTION

FIG. 1 is a front perspective view of a laser biostimulator for veterinary and human use showing my new design.

FIG. 2 is a top plan view thereof;

FIG. 3 is a front elevational thereof;

FIG. 4 is a bottom plan view thereof;

FIG. 5 is a rear elevational thereof;

FIG. 6 is a right side elevational thereof; and

FIG. 7 is a left side elevational thereof.
